[57] CLAIM

The ornamental design for a personal computer, as
shown and described.

DESCRIPTION

FIG. 1 is a front, right side perspective view of a per-
sonal computer showing my new design;

FIG. 2 is a top plan view thereof;

FIG. 3 is a left side elevational view thereof, the right
side being a mirror image, but for the specific key layout
on the keyboard;

FIGS. 4 and 5 are respectively a rear elevational view
and a bottom plan view of the monitor, the central
processor and keyboard being omitted for convenience
of illustration and purposes of disclosure;

FIGS. 6 and 7 are respectively a top plan view and a
rear elevational view of the central processor, the moni-
tor and keyboard being omitted for convenience of
illustration and purposes of disclosure;

FIGS. 8, 9, and 10 are respectively front, right side and
rear elevational views of the keyboard on an enlarged
scale, the monitor and central processor being omitted
for convenience of illustration;

FIGS. 11 and 12 are respectively right side and rear
elevational views thereof with the rear leg in an ex-
tended position.
